(57) **CLAIM**

We claim the ornamental design for an absorbent article, as shown and described.

DESCRIPTION

FIG. 1 is a perspective view of an absorbent article according to an embodiment of the present invention;

FIG. 2 is a top plan view of the absorbent article according to the embodiment of FIG. 1;

FIG. 3 is a side view of the absorbent article according to the embodiment of FIG. 1;

FIG. 4 is a bottom plan view of the absorbent article according to the embodiment of FIG. 1; and,

FIG. 5 is an end view of the absorbent article according to the embodiment of FIG. 1.
